UNITED STATES PATENT OFFICE

136,174

DESIGN FOR A SHAKER FOR SALT AND PEPPER

Gilford D. Adams, Butterfield, Mo.

Application June 10, 1943, Serial No. 110,421

Term of patent 3½ years

To all whom it may concern:

Be it known that I, Gilford D. Adams, a citizen of the United States, residing at Butterfield, in the county of Barry and State of Missouri, have invented a new, original, and ornamental Design for a Shaker for Salt and Pepper, of which the following is a specification, reference being had to the accompanying drawing, forming part thereof.

Figure 1 is a perspective view of a shaker for salt and pepper, showing my new design;

Figure 2 is a view similar to Figure 1, but showing the opposite side thereof; and

Figure 3 is a sectional view thereof.

I claim:

The ornamental design for a shaker for salt and pepper, as shown.

GILFORD D. ADAMS.
